United States Patent Office

Des. 223,222

Patented Mar. 28, 1972

223,222

BAG

Louis J. Christen, Jr., St. Louis, Mo., assignor to J. C. Christen Manufacturing Co., St. Louis, Mo.

Filed Mar. 28, 1969, Ser. No. 16,516

Term of patent 14 years

Int. Cl. D3—99

U.S. Cl. D87—3

FIG. 1

FIG. 2

FIG. 3

FIG. 5

FIG. 4

FIG. 1 is a side elevational view of a bag embodying my new, original and ornamental design;

FIG. 2 is a view showing the right side of the same bag;

FIG. 3 is an elevational view showing the opposite side of the bag of FIG. 1;

FIG. 4 is a view showing the left side of the bag of FIG. 1; and,

FIG. 5 is a top view of the bag.

I claim:

The ornamental design for a bag, as shown.
